APPARATUS FOR HANDLING VISCOSE SOLUTIONS

Hobart O. Davidson, Swarthmore, Pa., assignor to
 American Viscose Corporation, Wilmington,
 Del., a corporation of Delaware

Application March 1, 1944, Serial No. 524,583

7 Claims. (Cl. 18—8)

1

This invention relates to apparatus for handling viscose solutions. More particularly the invention has to do with the viscose during the ripening and the handling or feeding thereof to the product-forming room. The invention will be described for convenience in its application to a system of making rayon, but the system is equally applicable to the manufacture of regenerated cellulose sheeting, or to any other process in which viscose is used.

In the manufacture of rayon by the viscose process, cellulose xanthate is formed, ripened, filtered, is deaerated, and finally extruded through a spinneret into a coagulating bath.

In the conventional practice of today, batches of cellulose xanthate are dissolved in an aqueous caustic solution and three or four such charges blended to form a final viscose charge. These charges are sent to the ripening room, where they are confined in tanks, forced, usually by air pressure, through a filter press into other tanks, filtered, confined in the other tanks, and the processes of filtering and confining repeated until the viscose has reached the stage of ripeness suitable for delivery to the room wherein it is to be formed into the desired products. When this stage has been reached, the viscose charge is flowed into one of two or more "feed" or "spinning" tanks, from which it is delivered to the product-forming room. The viscose is forced from one feed tank, usually by air pressure or by positive displacement pumps, which may be assisted by air pressure on the tank, until the tank is substantially exhausted, then viscose is taken from the other feed tank or tanks, and so on.

In accordance with the present invention, the transferring of the viscose during ripening in succession through several filters and several groups of tanks is eliminated. Instead a large battery of ripening tanks are filled in rotation with the blended viscose which is then allowed to stay in these tanks until ripened to the proper extent, after which the ripened viscose is withdrawn in rotation from these storage tanks and is forced by positive displacement pumps through filters into the feed tanks, from which the viscose may be forwarded to the spinning machines in any suitable manner.

In order to provide an adequate supply of ripened viscose for the feed tanks, a large number of ripening tanks as compared to the number of feed tanks are needed, because of the long periods of ripening, usually several days, required. The present invention provides a sys-

2

tem for making it practical and economically feasible to handle the viscose in such a large number of tanks without encountering pumping difficulties resulting from long suction lines, and difficulties resulting from stagnation of the viscose in remote parts of the piping system, while withdrawing viscose from a given ripening tank.

The present invention has the advantages of reducing the amount of handling and pumping of the viscose during ripening, and of requiring relatively less equipment and supervision. It provides for blocking off a group or groups of the ripening tanks for drainage, cleaning, and refilling, while maintaining the circulation of viscose having a substantially uniform degree of ripeness through all pumps, and substantially all of the remainder of the piping system. It also delays filtration to permit the maximum agglomeration of filterable products, after which it is most effective.

The invention can best be understood by referring to the accompanying drawing, of which—

Figure 1 is a diagrammatic view of the piping system;

Figure 2 is a diagrammatic view showing one form of relief valve that may be used in accordance with the invention; and

Figure 3 is a diagrammatic view of a modified arrangement.

In Figure 1 there are shown a plurality of ripening tanks numbered 1 to 15. These tanks are fed from the viscose dissolvers by the header 16 and the branch lines 17 connected to the header by cocks 18, which are three-way except for that connecting the last tank 15, which is two-way. For discharging these tanks, they are associated in groups with separate headers. The number of groups may vary from two to five or more, and the number of tanks in each group may vary from three to six, more or less. As shown, however, there are three groups, each comprising five tanks associated with the headers 19, 20 and 21 respectively. Cocks 22, which are all of three-way type, except for the two-way type used for the tanks connected to the end of the headers, connect the discharge lines 23 from the tank bottoms to their respective headers. Each tank may be provided with a dump valve (not shown) at its bottom, which may be turned to connect or disconnect the tank proper from its discharge line 23.

Separate positive displacement pumps 24, 25 and 26 are connected to the respective headers 19, 20 and 21, through their suction lines 27, 28 and 29, and discharge into a common line 30,

which, as shown, doubles back on itself and leads to the filter 31. Another positive displacement pump 32 is connected between the discharge line 33 of filter 31 and the feed line 34 to a second filter 35 which discharges through line 36 connected to the suction side of pump 37, which discharges through line 38 into a third filter 39 from which a discharge line 40 may lead to the feed tanks 140 or through additional filtering equipment. The filters may be graduated so that each succeeding filter removes finer aggregates, though this is not essential.

By-pass lines 41, 42 and 43 connect the common discharge line at points therein beyond all of the pumps 24, 25 and 26 to the respective pump suction lines 27, 28 and 29 through three-way cocks 41', 42' and 43'. These by-pass lines contain valves 44, 45 and 46, which serve as relief valves as well as by-pass valves. These valves may be hydraulically operated and are controlled by the pressure-responsive controller 47 which is connected to line 33. This controller 47 may be of the conventional type which opens a valve in an air line 48 (shown dotted) when the pressure in line 33 exceeds a predetermined value to which the controller is set, and thus permits air to flow to the hydraulic relief valves 44, 45 and 46 through the air lines 49, 50, 51 and 52.

A by-pass line 53 connects the pump discharge line 34 with the pump suction line 33, a hydraulically-operable relief and by-pass valve 54 being provided therein. A controller 55 connected to line 36 is responsive to the pressure therein and operates the relief valve by admitting air to line 56 when the pressure in line 36 exceeds a predetermined value to which the controller is set.

Figure 2 shows diagrammatically the hydraulically operated relief and by-pass valve 54, which is the same as those used at 44, 45 and 54. The valve has ports 30' and 27' which are connected to lines 30 and 21 respectively. Port 30' opens into port 27' at 57 and 58, the latter opening being provided with a seat against which the valve 59 is normally pressed when closed. The valve stem 60 carries a piston 61 which is normally urged by the spring 62 to close the valve, but which is forced to open the valve when air is admitted through the connection 50' with air line 50. The small opening 57 serves to by-pass a small amount of viscose constantly.

Constant speed motors diagrammatically shown at 63, 64 and 65 are provided to drive the pumps 24, 25 and 26, respectively. These motors are preferably adjustable to any speed, so that any predetermined volume of viscose can be delivered thereby, and they are connected to the pumps by means of overdrive clutches, so that small idling motors diagrammatically shown at 66, 67 and 68, can operate the pumps at slow speed when the main driving motors 63, 64 and 65 are not in use. Alternatively each of the pumps 24, 25 and 26 may be connected to a constant speed motor through a reduction gearing transmission by which the pump may be driven alternately at high or low speeds when and as desired.

Constant speed motors 32' and 37' which are preferably adjustable in speed drive the pumps 32 and 37 respectively.

Each discharge header 19, 20 and 21 and its associated line 27, 28 and 29, may be provided with an off-line drain valve or cock 69, 70 and 71 respectively. Sight glasses may be provided at any point in the headers 19, 20 and 21, such as on the far side (with respect to the pump) of each of

the intermediate tanks of a given group, so that it can readily be determined when a given tank and section of the header has been drained. There is specifically shown in Figure 1 the sight glasses 72, 73 and 74, just in advance of the cocks 41', 42' and 43'. Sources of light 75 are provided on one side of the sight glasses, while electric eyes 76, 77 and 78 on the other side are provided with suitable conventional relays and connections with their respective main driving motors and idling motors and connections 41', 42' and 43' so that when a given header has been drained, the main driving motor is stopped, the idling motor is started, and the respective cock is blanked toward the header while permitting flow through the respective by-pass line.

A modification of the arrangement of tanks and pipe lines is shown in Figure 3, in which the important parts corresponding to those shown in Figure 1 are designated by the same reference characters as in Figure 1, with the addition of the postscript *a*.

The operation is as follows: Dissolved viscose is delivered in rotation to the ripening tanks, illustratively in the order of their numerical designations. When ripening has proceeded to such an extent that withdrawal from each of the tanks in sequence is in order, the cocks in the headers, except that associated with the first tank filled, which is tank 1 in the present instance, are blanked toward their tanks; cock 41' is turned to connect the header 19, the by-pass line 41, and the pump 24; and the main driving motor 63 operates the pump 24. Cocks 42' and 43' are turned to blank off their respective headers 20 and 21 while connecting the by-pass lines 42 and 43 with the pumps 25 and 26, which are operated at low speed by the idling motors 67 and 68.

Each of the pumps 24, 25 and 26 and 32 is adjusted to deliver when driven by its respective main driving motor somewhat more than pumps 37, the excess in each case being discharged around the by-passes associated with the respective pumps.

Pressure controller 55 maintains a constant small positive pressure in the suction side of pump 37 by operating relief valve 54 when the pressure at that point exceeds the predetermined value. Similarly a small constant positive pressure is maintained on the suction side of pumps 32 by the controller 47 which operates one or more of the relief valves 44, 45 and 46 when the predetermined pressure is exceeded. It will thus be seen that series filtration is obtained with controlled pressure on each filter just sufficient to operate the filter at the desired rate of flow. Pump 37, of course, determines the rate of filtration.

Thus each of the first group of tanks will be emptied in succession, upon the conclusion of which the header 19 is drained, cock 41' is blanked toward the header, leaving the by-pass 41 open to the pump 24. The main motor 63 is stopped and motor 66 is started. The cocks in header 20 are then set, so that tank 6 can be drained through cock 42' which also is open to the by-pass line 42. Motor 64 then operates the pump 25.

After emptying the second group of tanks, withdrawal is performed in similar fashion from the tanks in the first or any additional groups.

While withdrawal is made from one group of tanks, the tanks in other groups may be refilled, cleaned and drained through the off-line valve corresponding to 69, 70, or 71, and repaired, or they may simply be storing viscose for ripening

in preparation for subsequent transfer through the filters to feed tanks.

It is to be understood that alternate or relief equipment may be provided at any stage of the system. For example, alternate filters may be provided to permit taking some of them out of the line temporarily for redressing.

Thus the invention provides a system for handling viscose in a large number of tanks in accordance with which positive displacement pumps with relatively short suction lines are provided for forcing the substantially completely ripened viscose through a series of filters. There is also provision for controlling the pressure on a series of filters to maintain the minimum pressure on the filters that is needed at any time during the filtering cycle to operate at the desired flow, and thus correlating the flow through the several filters to obtain efficient and economical filtration at a substantially uniform rate of flow. In addition, there is provision for continuous circulation of the viscose through all parts of the system at all times except when one or more of the groups of tanks are blanked off after drainage, for refilling and the like. In this way there is no opportunity for stagnation of viscose in any portion of the system.

Certain subject matter other than that claimed herein is the subject of claims in applicant's copending application Serial No. 601,901, filed June 27, 1945.

It is to be understood that changes and modifications may be made without departing from the spirit of my invention, as defined in the appended claims.

I claim:

1. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, a common header, separate branch lines connecting the respective discharge headers to the common header, pumping means in each of said lines, separate by-pass lines connected to the respective branch lines on the suction side of the pumps therein and to the common header beyond all of the branch line connections thereto.

2. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, filtering means, a common header connected to the filtering means, separate branch lines connecting the respective discharge headers to the common header, pumping means in each of said lines, separate by-pass lines connected to the respective branch lines on the suction side of the pumps therein and to the common header beyond all of the branch line connections thereto.

3. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, filtering means, a common header connected to the filtering means, separate branch lines connecting the respective discharge headers to the

common header, pumping means in each of said lines, separate by-pass lines connected to the respective branch lines on the suction side of the pumps therein and to the common header beyond all of the branch line connections thereto, means for selectively shutting off any of the discharge headers from its associated pumping means without shutting off the by-pass line from the respective pumping means, means for selectively opening any of the tanks to its associated header, means for selectively driving any of the pumps at one speed for emptying the tanks and means for selectively driving any of the pumps at a lower speed for circulating a portion of the dispersion through the by-pass during periods when another of the pumps is emptying a tank of another group.

4. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, a plurality of filtering means, pipe-lines connecting the filtering means in series, a common header connected to discharge into the first filtering means, pumping means connecting the discharge headers with the common header, additional pumping means for feeding each filtering means beyond the first from the discharge of the preceding filtering means, by-pass lines connecting the discharge side of the pumping means beyond each filtering means except the last with the suction side of the respective pumping means and means for controlling the discharge pressure of each filtering means except the last.

5. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, a plurality of filtering means, pipe-lines connecting the filtering means in series, a common header connected to discharge into the first filtering means, pumping means connecting the discharge headers with the common header, additional pumping means for feeding each filtering means beyond the first from the discharge of the preceding filtering means, by-pass lines connecting the discharge side of the pumping means beyond each filtering means except the last with the suction side of the respective pumping means, and means for maintaining predetermined substantially constant pressures on the suction sides of each of the pumping means except that in advance of the first filtering means.

6. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, a plurality of filtering means, pipe-lines connecting the filtering means in series, a common header connected to discharge into the first filtering means, separate branch lines connecting the respective discharge headers to the common header, pumping means in each of said lines, separate by-pass lines connected to the respective branch lines on the suction side of the

pump therein and to the common header beyond all of the branch line connections thereto, additional pumping means for feeding each filtering means beyond the first from the discharge of the preceding filtering means, by-pass lines connecting the discharge side of each of the additional pumping means except the last with the suction side of the respective pumping means, and means for controlling the discharge pressure of each filtering means except the last.

7. Apparatus for handling dispersions of viscose and other materials subject to change in properties with passage of time preparatory to delivery to the product-forming stage comprising a large number of tanks, at least two discharge headers, each of the headers being associated with a separate group comprising a plurality of the tanks, a plurality of filtering means, pipelines connecting the filtering means in series, a common header connected to discharge into the first filtering means, separate branch lines connecting the respective discharge headers to the common header, pumping means in each of said lines, separate by-pass lines connected to the respective branch lines on the suction side of the pump therein and to the common header beyond all of the branch line connections thereto, additional pumping means for feeding each filtering

means beyond the first from the discharge of the preceding filtering means, by-pass lines connecting the discharge side of each of the additional pumping means except the last with the suction side of the respective pumping means, and means for controlling the discharge pressure of each filtering means except the last, each of said pressure-maintaining means comprising a relief valve in the by-pass line in advance of the respective filtering means, and a member connected to the discharge line of the respective filtering means responsive to pressure therein connected to the relief valve to open it when a predetermined pressure is exceeded in said discharge line.
